CONVERTIBLE DOLL

Margaret De Vries, Roslyn Heights, N. Y.

Application February 6, 1942, Serial No. 429,713

9 Claims. (Cl. 46—153)

This invention has general reference to flexible toys and, more particularly, relates to dolls of the type generally known as reversible or which, by manipulation, are changeable to distinctive forms for greater attraction and amusement.

Dolls of the type referred to are mainly of two forms, the one comprising plural body portions individually adapted to depict different characters or images, said portions being aligned in reverse relation and having respectively associated contrasting clothing; whereas the other form has included differing head sections attached to a garment in opposing relation by a common juncture, said garment being of reversible species and designed to envelope one of the head sections when the other is exteriorly exposed, or vice versa.

The primary object of this invention is to furnish an improved convertible doll, of bi- or multi-partite formation, comprising a hollow body section having an access-opening within its surrounding limits, as well as multiple heads and limbs; one head or heads along with associated limbs being insertable and closable within the hollow body, when the desired head with the associated limbs are external thereof, whereby fullness and shape is given to such hollow body and the result more closely simulates a real doll than heretofore.

Another object is the provision of a rag doll of the type specified in the preceding paragraph which is easily convertible to simulate extreme characteristics, such for instance as that of a sleeping infant and that of one awake.

A further object of this invention is the provision of a doll of the form above indicated which by reason of its characteristics is particularly attractive to children, and by reason of its simple manipulation is educational.

It is also an additional object to furnish a convertible rag doll which in either of its formative positions provides comparatively firm and compact differing personalities.

For the purpose of illustrating this invention, there is shown in the accompanying three sheets of drawings a typical form thereof which is, at present, considered to be preferable; since such form will give satisfactory and attractive results. It is, however, to be understood that the various components of which this invention consists may be otherwise shaped and variously arranged in assembly with corresponding advantages, hence the embodiment chosen for illustration herein is not limited to the precise details shown and described, whereas the concluding claims more

particularly express the features of novelty over the prior art.

In the drawings:

Fig. 1 is a front view of the convertible doll of this invention and illustrating one of the characters which it is capable of representing.

Fig. 2 is a rear view of the preceding figure, with the outer garments in section to better disclose otherwise hidden structure.

Fig. 3 is a rear view of the doll with the outer garments removed for clearer showing of the initial step of transforming said doll to illustrate the other character which it is designed to represent, or with the opposing and reversely related head withdrawn, as later on fully explained.

Fig. 4 is a partly broken view, similar to the preceding, showing the second step of converting the doll; or with the arms withdrawn; and the lower-half of the body portion turned-up.

Fig. 5 is a side view illustrating the third step, or with the legs for the second character drawn out with the outer garments omitted, to obviate confusing illustration, and the arms and head of the first character in process of infolding for insertion into the lower-half of the body portion.

Fig. 6 is a front, or inverted, view of the doll second character, incidental to completion of the third step shown by Fig. 5.

Fig. 7 is a face view of the doll in second character position and clothed in an appropriate sleeping garment.

Fig. 8 is a side view of the preceding, with the outer garment in section for clearer illustration of an otherwise obscured feature.

Figs. 9 to 12, inclusive, are approximate developments of basic parts involved in making the doll and, all of which, are hereinafter fully explained.

In describing the form of this invention exemplified in the above captioned drawings, herewith, specific terms will be employed for the sake of clarity, but it is to be understood the scope of said invention is not thereby restricted; each such term being deemed to embrace all equivalents which perform the same function for an analogous purpose.

The improved convertible doll shown in the drawings, it is to be remarked, may be conveniently termed as a two-in-one embodiment, or as including contrastingly-related dolls comprehensively designated as 13 and 14. The one doll 13 for instance is substantially foldable within the body of the other doll 14, and vice versa, in order to show the respective characters represented thereby when clothed. Fig. 1 illustrates

the doll 13 dressed in a two-piece playsuit comprising a dress-jacket or guimpe 15 with suspender overall-slacks 16, the latter being provided with a drop-seat 17, Fig. 1, and shoulder straps 18, said shoulder straps being attached at the rear to the back of the guimpe 15. The back part of the guimpe may be conveniently provided with spaced buttons 20 and an intervening button 22, with similar stitching 23, at the mid-region of the waist-line. These buttons 20, 22 may serve for connection thereto of the seat 17 by aid of button-holes 24, in the latter. To prevent removal of the guimpe 15 and also better safeguard against disarrangement of the appearance of the doll, the sleeves are puffed at 25 and preferably secured to the arms 26 by stitching 27, see Figs. 1 and 2.

Referring now to the contrastingly attired doll 14, see Figs. 7 and 8 to best advantage, it will be seen said doll is clothed with a sleeping suit 28, preferably of the one-piece style and having a slit 29, for access to the buttons 20, 22, aforesaid.

The two-in-one doll, herein illustrated by way of example, conveniently comprises a blank 34, Fig. 9, preferably including a main or body section 35 of approximately rectiform contour or having parallel sides 36 with diagonally-related outwardly-curved shoulder-defining edges 37, separated by combined neck and head simulating parts 38, 39, respectively. In addition the body section 35 also embodies opposingly-directed and, for convenience of description, hereinafter termed "upper" and "lower" pairs of half arm-forming sections 40, 40, 41, 41. Applied to one face of the main blank 34 are the complementary or upper and lower shoulderette-like pocket-forming components 19, 33 hereinbefore mentioned, each such component embodying a semi-body section 42 and half arm-forming sections 43, as well as combined neck and head simulating parts 44, 45. Now it will be readily understood that when the components 19, 33 are reversely laid on the main blank 34 with the straight edges 46 of the former adjoining the transverse median of the latter, as indicated by the dotted line 47 across Fig. 9, and said parts are united by sewing along the surrounding dot-and-dash fine line 48 in said figure, that a hollow structure results; such structure having a transverse slit or access-opening 49, Fig. 3, defined by the adjoining straight edges 46. The hollow structure thus formed is next turned inside-out, whereupon the respective limbs formed by the confronting upper half-arm sections 40, 43 and the lower half-arm sections 41, 43, as well as the reversely directed heads formed by the overlaid parts 38, 45 are packed or "stuffed," with an appropriate filler—not shown—such as cotton-wool to give substance thereto, and closed-in by seamings as indicated by the respectively associated heavy dot-and-dash lines 50, 51. Each leg is formed from complementary blanks 52, 53, Fig. 12, by sewing said blanks together along the light dot-and-dash lines 54, indicated in said figure, next turning the structure inside-out and then "stuffing" it with the appropriate filler, and thereafter seaming the thus formed limbs to the shoulder-defining edges 37, Fig. 9, of the main structure, previously described, along the heavy dot-and-dash lines 55 of Fig. 12, in an obvious manner. It will be understood, that the doll body includes opposingly-related pockets defined by the blank 34, and the respective shoulderette components 19, 33 each of which, when in one position, will

conceal one pair of legs and allow a head and one pair of arms to be exposed to view; while when in an inverted position, it will substantially conceal the said head and arms and expose the aforementioned legs.

The two-in-one doll thus formed is now ready for dressing in suitable attire, for example firstly with the garments 15, 16 as described in connection with the first form of doll designated 13, and thereafter with the other garment 28, as explained in connection with the second form of doll 14, or vice versa when desirable, it being readily understood that the respective buttons 20, 22 are affixed, as hereinbefore set forth, incidental to the dressing operation. Obviously the doll garments may have appropriate legends 56, 57 embroidered thereon to indicate the desired characterizing condition, such as being awake or asleep; whereas the respectively associated portions of the head sections 39, 45 can have faces 58, 59 stencilled thereon, or such faces may be hand-painted or otherwise formed, in reverse relationship with respect to the general plane of the doll; and finally suitable head-dress 60 is preferably attached to or formed on the rear of the respective faces 58, 59.

Assuming now that the doll is in the form shown by Fig. 1, and it is desired to change the same to that of Fig. 7, the buttons 20, 22 are first released from connection with the drop-seat 17 and the latter opened as shown in Fig. 3 incidental to drawing out the doll head bearing the face 59 through the slit or access opening 49, from the upper pocket defined by the parts 35 and 42, when the associated arms and legs 61, 62 are individually and successively withdrawn from said pocket as readily understood from Figs. 4 and 6 more particularly. The legs 63 of the first form of doll 13 are next folded-up within the pocket defined by the lower parts 35 and 42, as best shown by the dotted outlines in Fig. 5, with consequent retroversion or turning-inside of said parts, whereupon the arms 26 and head bearing the face 58 are bent over and inserted in the just referred to pocket along a path typically indicated by the curved arrow on Fig. 5. The garments are now re-arranged and the let-down seat 29 connected to the buttons 20, 22, in the manner hereinbefore explained. Obviously the operation just described is reversed when the doll 14 is to be changed to the form 13, and may be easily learned by a child, with instructive and educational advantage.

From the foregoing the merits and fascinating attractiveness of the herein disclosed doll will be clearly appreciated, while it is to be understood various other forms and arrangements of the doll are within the contemplation of this invention. Still further the improved convertible-doll may be made to portray different characters than illustrated by the drawings, and other costumes or clothing employed, without in any way departing from the spirit or scope of this invention as more concisely expressed in the following claims.

Having thus described my invention, I claim:

1. A multiple-character convertible toy comprising a flexible, hollow structure having an access-slit within its planar confines to define opposing sections; means forming sets of body simulating members extending outwards from the hollow structure; and means for closing the access-slit, when one set or sets of the body simulating members are folded into the hollow

structure, to complete representation of the selected character.

2. A multiple-character convertible toy comprising a flexible material hollow body structure having an access-slit across one side to define counterpart sections; plural sets of body members extending outwards from the body structure; and attaching means effective to close the access-slit, when one set or sets of the body members are folded within the hollow structure, to complete representation of the selected character.

3. The combination of claim 2, wherein the body structure is of approximately rectiform contour; the respective sets of body members comprise opposingly-related head and limb sections pivotal relative to the body structure; and the individual characters are clothed in distinctive outfits.

4. A two-in-one convertible doll comprising a flexible material hollow body portion including means providing an access-slit transversely across one major side thereof to define opposing pocket sections; means defining duplicate head, arm, and leg, simulating members pivotally related to the body portion and extending outwards therefrom in opposing directions; appropriate filler in the respective head, arm, and leg, simulating members to give substance thereto; and detachable means for effecting closure of the access-slit, when one pair of legs with the associated arms and head are folded into the hollow body portion, to complete representation of one doll.

5. The combination of claim 4, wherein the respective dolls are clothed in distinctive dresses, each such dress including a regional flap, and means whereby such flap is releasable from and attachable to an underlying portion of the dress.

6. A body portion for convertible dolls of the type described comprising a main section of

somewhat rectiform contour with reversely directed neck, head, and shoulder, simulating parts, as well as spaced pairs of semiarm-forming lateral projections; opposed shoulderette-like components each embodying a half-body portion with a head-simulating and semiarm-forming projections corresponding with the first mentioned analogous parts, and means joining the surrounding edges of the main section with the overlaid confronting edges of the opposed shoulderette-like components to define a hollow structure having an access-slit defined by the adjoining edges of said components and incidental to formation of counterpart pockets in said structure.

7. A body portion for convertible dolls as recited in claim 6, wherein the main section is defined by parallel sides and intervening outwardly curved diagonally-related shoulder defining ends, said shoulders being separated by a neck and head simulating extension, and the spaced pairs of half arm-forming projections extend laterally from the terminal sections of the parallel sides with outward merging into the shoulder defining ends.

8. A body portion for convertible dolls as defined in claim 6, wherein the joined main section and opposed shoulderette-like components are wholly turned inside-out, appropriate filler is packed into the head and arm simulating parts, and said parts are rendered pivotal by closure-seaming across the neck region and along lines substantially paralleling the vertical centerline of the doll.

9. A body portion for convertible dolls as defined in claim 6, wherein pairs of pre-formed legs are flexibly attached to the shoulder simulating parts, and said legs are foldable within the hollow structure through the access-slit defined by the shoulderette-like components.

MARGARET DE VRIES.
